UNITED STATES PATENT OFFICE.

JOHN A. SCHOFIELD, OF WASHINGTON, DISTRICT OF COLUMBIA, AND CHARLES W. HALL, OF STAMFORD, CONNECTICUT.

METHOD OF HANDLING HIGH EXPLOSIVES.

1,402,971.

Specification of Letters Patent. Patented Jan. 10, 1922.

Application filed November 19, 1919. Serial No. 339,208.

To all whom it may concern:

Be it known that we, JOHN A. SCHOFIELD and CHARLES W. HALL, citizens of the United States, residing at Washington, District of Columbia and Stamford, Connecticut, respectively, have invented new and useful improvements in Methods of Handling High Explosives, of which the following is a specification.

10 This invention relates to a method for handling high explosives and more particularly to loading projectiles or charges with the high explosive or the recovery of such explosives from defective containers.

15 This invention will be hereinafter described with relation to its application to a method of handling of T. N. T. or similar high explosives although it is, of course, to be understood that without material modification various features in the method of handling the explosive may be carried out 20 on other materials without departing from the invention.

25 In the apparatus heretofore employed for this purpose separate machinery has been used for stirring the high explosive and for pounding the same through grids prior to introducing the explosive into the melting apparatus. The use of such method and apparatus increases the liability of fire and 30 explosion through frictional contact and involves great expense in the installation of such machinery and its subsequent operation. Much difficulty has also been experienced 35 in controlling the temperature of the plastic explosive. The gases generated and this type of apparatus greatly endangered the workmen to gas poisoning and also subjected them to the above mentioned dangers 40 of fire and explosion. It is one of the objects of my invention to overcome these and other objections by the provision of a simple and practical process or method of handling high explosives.

45 I am aware that melting high explosives in water is now used by manufacturers for the purpose of purification. When the trinitration is completed the melting explosive is first washed in contact with hot water by 50 stirring in steam jacketed kettle. After settling the explosive is drained through a valve and comes into contact with jets of cold water which break it up into pellets. These pellets are remelted by stirring in

steam jacketed kettles with hot water. It 55 will be noted that although the water is used to facilitate the melting the steam jacketed kettle is also used. The various advantages of this invention can be more readily understood and the novel features thereof will 60 be more apparent from the following description of the accompanying drawings in which:

Figure 1 is a front elevation, partly in section, of the complete apparatus. 65

Figure 2 is a top plan of the same, showing one of the covers removed.

Referring to the drawings, 1 indicates steel tanks in which the explosive is placed. The tanks 1 have inverted pyramidal bottoms 2. Removable covers 3 provided with steam vents 4 and supply chutes 5 are secured on the tanks 1. Bars 6 are disposed transversely near the bottom of the tanks 1 for supporting mine cases. Feed valves 7 75 are placed in a water supply line 8 adjacent the tanks for supplying same with water. Drain valves 9 are provided in drain pipe 10 whereby the tanks 1 may be emptied or overflow taken care of. A suitable source 80 of steam supply 11 having a regulating valve 12 and hydrokineters leads into a saturator 14. From the saturator 14 the steam passes through pipes 15 and 16 and hydrokineters 18 into the tanks 1 containing water 85 previously supplied to the tanks 1 by the pipe 8 and valve 7. Suitable valves 17 are provided for controlling the admittance of steam into tanks 1. At the apex of the bottoms 2 discharge pipes 19 having gate valves 90 20 and a strainer 21 communicate with supply pipe 22 having thereon a discharge 95 measuring valve 23.

The operation is as follows:—When the explosive is to be melted the tanks 1 with 95 covers 3 in place are filled about half full of water from valve 7 and pipe 8. Steam valves 17 are opened admitting steam 100 through regulating valve 12 at a constant pressure of twenty-five pounds to hydrokineters 13 and 18. The jets from the hydrokineters 13 and 18 agitate or stir the water and raise it to the boiling point. The saturator 14 is introduced to insure a constant temperature of 256° F. since the steam 105 from the regulating valve 12 will be superheated at amount depending upon boiler pressure and transmission losses.

The crude explosive is now introduced into the first tank 1 through chute 5, no crushing being necessary, until the desired charge is contained in the tank. The steam entering through hydrokinetics 18 produces a violent agitation of the whole mass, bringing every particle into contact with the hot water and keeping it in circulation until it is melted. The tendency of the T. N. T. having a density of approximately 1.58 to settle to the bottom will be prevented except in the pipe 19 below the hydrokinetics 18. When the T. N. T. is melted the valve 17 is closed and the contents of the tank allowed to settle for approximately forty minutes causing the water to rise to the surface and leaving practically dry T. N. T. in the pipes and at the bottom. The T. N. T. is now ready to pour.

10 The valve 20 belonging to the tank now ready to pour is opened, allowing the T. N. T. to pass through the strainer 21 to the valve 23 from which the explosive can be poured into the container. T. N. T. gauge 24 is 15 to show the valve operator when he no longer has enough for a full charge, thus preventing pouring water into a partly completed charge.

20

30

35

40

It is apparent that the using of the two tanks, alternately filling and melting in one tank while the T. N. T. in the other tank is settling and being poured, will permit constant operation of the apparatus. This independent operation of the two tanks is facilitated by a common source of steam supply 15, having independently operative shut off valves 17. The same is true of the water supply line 8 and valve 7. The tanks 1 and steam pipes 15 are heat insulated and all T. N. T. pipes and valves are steam jacketed or wound with steam pipe as at 25.

In order to use this equipment for the reclaiming of T. N. T. from damaged cases, it is necessary to construct the tanks 1 large enough to hold any case in such a position as to permit of its draining when the charge is melted. The charges to be melted are placed on the bars 6, with the case opening down. The case is completely covered with water from the supply line 8 and valve 7. Steam is supplied from steam line 15 and

valve 17, and otherwise the operation is similar to that of melting T. N. T.

From the above it will be seen that this invention is of a simple, practical and highly efficient character well adapted to accomplish, among others, all of the objects and advantages herein set forth.

What I claim is:

1. The method of melting high explosive 60 wherein water in a receptacle is raised to the boiling point by jets of steam previous to introducing the high explosive in said receptacle.

2. The method of melting high explosive 65 which consists of practically filling a closed receptacle with water, raising said water to the boiling point by jets of steam and introducing crude high explosive into said receptacle where it is thoroughly agitated 70 and reduced to a plastic state.

3. The method of melting and recovering high explosives which consists of subjecting damaged cases containing high explosive to jets of steam whereby the explosives may 75 be drained from said cases.

4. The method of melting and recovering high explosives wherein damaged cases containing the explosive are submerged in water and subjected to jets of steam whereby the 80 explosives may be drained from said cases.

5. The method of melting and recovering high explosives wherein damaged cases containing the explosive are supported by suitable means within a container and subjected 85 to jets of steam whereby the explosives may be drained from said cases.

6. The method of melting and recovering high explosives which consists of filling a closed receptacle with water, raising said 90 water to the boiling point by jets of steam, and introducing damaged cases containing high explosive into said receptacle whereby the explosive is reduced to a plastic state whereby the explosives may be drained from 95 said cases.

Signed at Washington, District of Columbia, this 10th day of September, 1919.

JOHN A. SCHOFIELD.

Signed at Missoula, Mont., this 25th day 100 of September, 1919.

CHARLES W. HALL.
